UNITED STATES PATENT OFFICE

156,409

PEANUT VENDING MACHINE

Gilbert Courshon, Chicago, Ill., assignor to Tropical Trading Company, Incorporated, a corporation

Application February 3, 1949, Serial No. 672

Term of patent 14 years

(Cl. D52—3)

To all whom it may concern:

Be it known that I, Gilbert Courshon, a citizen of the United States, residing at Chicago, in the county of Cook and State of Illinois, have invented a new, original, and ornamental Design for a Peanut Vending Machine, of which the following is a specification, reference being had to the accompanying drawing, forming part thereof.

Fig. 1 is a front perspective view of a peanut vending machine, showing my new design; and Fig. 2 is a side elevational view thereof.

I claim:

The ornamental design for a peanut vending machine, as shown.

GILBERT COURSHON.
